UNITED STATES PATENT OFFICE.

JAMES J. HARKINS AND JOHN HARKINS, OF PITTSBURG, PENNSYLVANIA.

CAR-BRAKE.

SPECIFICATION forming part of Letters Patent No. 337,579, dated March 9, 1886.

Application filed September 2, 1884. Serial No. 142,081. (No model.)

To all whom it may concern:

Be it known that we, JAMES J. HARKINS and JOHN HARKINS, both citizens of the United States, and residents of Pittsburg, in the county 5 of Allegheny and State of Pennsylvania, have invented a new and useful Improvement in Car-Brakes, of which the following is a specification.

Our invention relates to means by which 10 the movement of the axle and wheel is utilized to apply the brakes.

Our invention consists in the construction hereinafter described, and pointed out in the claims.

15 In order that our invention may be fully understood, we will proceed to describe it with reference to the accompanying drawings, in which—

Figure 1 is a side elevation of the parts 20 within and without the casing, the parts without being removed and a portion of the casing being omitted. Fig. 2 is a section on line with the axle. Fig. 3 is an inner end view, a portion of the casing being omitted. Fig. 4 is a 25 face view of the disk and spider, the line of travel of the latter to eccentric position being indicated by an arrow through the center, the circular arrow indicating the lateral resistance of the vibrator. Fig. 5 is a face view of the 30 slide and guide, the latter being removed. Fig. 6 is a face view of the spider.

W is a car-wheel, and H a car-axle adapted to receive our improvement.

A is a disk divided for ready application to 35 the wheel around the axle and securely bolted together and to the wheel. The disk is formed with a recess to fit the hub of the wheel, a concave face to receive a spider, and radial recesses *a'*, forming projections or lugs *a*.

40 B is a spider formed with convex inner side to fit the concavity of the disk, and having T-shaped arms or lugs *b* working between the projections or lugs *a* in the recesses *a'* of the disk. The outer side of the spider is flat.

45 Also, surrounding the axle is a sleeve, C, having a conical head, C'', at the disk end, and at the outer end longitudinal slots C' and flanged collar C'.

F is a collar surrounding the slotted end of 50 the sleeve and secured to the axle through the

slots by means of bolts. Over this collar works the flange of the sleeve-collar.

D and D' are the two parts of a block or vibrator sliding on the sleeve. Between the block and sleeve, in rear of the head, is a 55 spiral spring, S', for pressing the head of the sleeve into the central opening of the spider, and thus retain the latter in normal position. The forward end of the block is inclined, as shown, and when it is brought to bear on the 60 spider it shifts the latter to the eccentric position shown in Figs. 2 and 4.

D² and D⁴ are straight grooves and D³ and D⁶ inclined grooves for the pin K of a lever, J. The inclined grooves, like the straight 65 grooves, meet at their outer ends and intersect the outer ends of the latter. The inclined grooves, and also the straight grooves, meet at their inner ends. On the outer end of the block is formed a circular depression, forming an 70 annular projection beveled on the inside, to provide a bearing, D⁷. An outwardly-inclined radial opening is made in the projection to provide a bearing, D⁸.

g' g are two parts of a guide loosely mounted 75 on the sleeve between the fixed collar F and the sliding block D D'. The parts are secured together by plates g' g³, forming flanges, on which is guided a slide, E, formed with projections E' E² E³ and E⁵ E⁶. The projections E² and E³ bear on the annular projection 80 of the block, the projection E' bears on the collar F, and the projections E⁵ E⁶ on opposite sides of the flange of collar C'.

I is the casing surrounding the internal 85 mechanism, formed with a pocket, I', to receive the spider when the latter is in eccentric position, and having a projection, J', to which is hinged a lever, J. The casing is also formed with a guide, I², on the outside. The lever 90 J has a central pin, K, working in the grooves of the block, and a pin, L, at its extremity, connected to a slide, X, in the guide I².

S is a rock-shaft mounted transversely of the axle, to which are secured at nearly opposite 95 sides the levers T and R. The lever T extends into a recess in the upper end of the slide E, to connect the slide and the shaft, by which the latter is adapted to operate the former. The other lever, R, engages a stud, Q, 100

on a worm-wheel, P, mounted on a projection, P', on the casing.

V is a pitman connecting a crank, u, on the worm-wheel shaft with a slide, W', in the 5 guide I², the latter slide and that, X, bearing against each other.

Beneath the guide I² on the casing is a lug, m, and to this lug is pivoted by pintle n² a toothed segment, O, engaged by the worm-wheel P, and having a lever-arm, n.

n³ is the brake-chain, secured through eye n⁴ by thumb-nut n⁴ to the lever-arm.

n⁵ is a cord by which the tension of the chain is adjusted.

15 From the condition of rest the parts are operated as follows: The shaft S being rocked toward the wheel, the lever T will lower the slide E, the projection E' bearing on the collar F, the projections E² and E³ on the bearings D⁶ and D⁷, respectively, and the projections E⁵ E⁶ bearing on the flanged collar, the sleeve C will be retracted and the block D advanced, compressing the spring S', as shown in Fig. 2, and causing the spider to assume

25 the eccentric position shown. In the meantime the first revolution of the block D carries vibrating lever across by causing the pin K to enter one or other of the inclined grooves. The upper end of the lever moves the slides

30 X W', pitman V, crank u, worm-wheel P, and sector O, causing the arm of the sector to tighten the brake-chain. The spider being caused to assume an eccentric position, the T-shaped arms thus projected occupy a position shown in Fig. 4, the head of an arm locking with one of the projections a on the disk A.

35 By moving the rock-shaft S in the opposite direction the lever R will strike the stud Q on the worm-wheel and return the latter, its connections, and brake-chain to normal condition, while the other lever, T, being elevated at the same time, will lift the slide E and permit the sleeve, block, spider, and vibrating lever to be returned to normal condition by the release of spring S'.

45 It is evident that the brake will operate without the sleeve or spring, as it will be seen that when the lock is removed from the back of the block the spider forces the said block laterally, causing it to regain its normal position, and so retains it.

Having thus described our invention, the following is what we claim as new therein and desire to secure by Letters Patent:

1. The combination, with a wheel and an 55 axle, of a sliding block, D D', a slide, E, a spider, B, and a disk, A, substantially as set forth.

2. The combination, with a wheel and an axle, of a sleeve, C, a sliding block, D D', a 60 slide, E, a spider, B, a disk, A, and a spring between the sleeve and the block, substantially as set forth.

3. The combination of a wheel, an axle, a disk having a concave face, and projections 65 forming recesses, a spider fitting the concave face and having arms occupying the recesses in the disk, a sleeve having a conical head working in the spider, a sliding block on the sleeve, a slide to advance the block and retract the sleeve, and a spring to retract the block and advance the sleeve, substantially as set forth.

4. The combination of the disk, spider, 75 sleeve, block, spring, flanged collar, fixed collar, and slide E, having projections E' E² E³ E⁵ E⁶, substantially as set forth.

5. The combination of the disk, spider, sleeve, slide, spring, a sliding block formed with inclined face bearing on the spider, and 80 grooves D² D⁴ D³ D⁵, and a vibrating lever, J', having a pin, K, occupying the grooves, substantially as set forth.

6. The combination of the disk, spider, block, spring, slide, and rock-shaft having lever for lowering and lifting the slide, substantially as set forth.

7. The combination of the vibrating lever J, slides X and W', pitman V, crank u, worm-wheel P, sector O, having an arm, n, and 90 brake-chain, substantially as set forth.

8. The combination of the rock-shaft S, having lever R, the worm-wheel P, having stud Q, sector O, having lever-arm n, and a brake-chain, substantially as set forth.
